PNEUMATIC SENDING VALVE

Leon N. Hampton, New York, N. Y., and Oyvind N. Giertsen, Bloomfield, N. J., assignors to Bell Telephone Laboratories, Incorporated, New York, N. Y., a corporation of New York

Application July 29, 1932, Serial No. 625,566

2 Claims. (Cl. 302—2)

This invention relates to pneumatic ticket distribution systems and more particularly to a type of sending valve used in such systems.

The object of this invention is to improve the construction and operation of such a valve.

A feature of the invention is the provision of a mechanism whereby a pressure exerted on a bar is effective to operate the valve preparatory to the introduction of the ticket in the pneumatic tube.

Another feature is the provision of a frame detachable from a base which is, in turn, permanently soldered to the pneumatic tube, the base serving as a seat and support for the valve.

This arrangement of parts greatly facilitates the machining of the base and the adjustment of the valve on its seat, while correspondingly decreasing the manufacturing cost of the apparatus.

Another feature is the provision of a rack or grid element formed with the frame whereby the air is drawn into the pneumatic tube from both sides of the ticket in order to facilitate its entrance into the tube, the rack also serving for guiding the ticket toward the valve and reducing the liability of foreign particles entering the tube with the consequent stopping of the tickets while in transit therein.

Fig. 1 is a top assembly view;

Fig. 2 is a side view with portions of the frame cut away and showing the valve in the open position;

Fig. 3 is a side view showing the frame removed from the base and the valve in the closed position; and

Fig. 4 is a diagrammatical view of a circuit and the air inlet adjusting mechanism controlled by the operation of the valve.

In the drawing, 10 indicates a metallic tube on which a base 11 is permanently secured as by soldering. The base is formed with bearing portions 12 and 13 shown in Fig. 1 for supporting a shaft 14 on which a valve 15 is pivoted.

On the under surface of valve 15 is mounted a pad 18 which is preferably made of relatively soft material such as rubber, held securely thereon by a metallic strip 19 and screws 20 and 21, shown in Figs. 1 and 2. The undersurface of pad 18 fits the top surface of base 11 which is accurately machined to form a seat for the pad 18 provided for closing registering apertures 16 and 17 in the base 11 and tube 10, respectively.

The valve 15 is provided with a plate 22 loosely fitted between lugs 23 and 24 and held in place by a spring 25 having one end abutting the head 55 of a stud 26 secured to the valve 15 as by riveting.

The plate 22 has a hook-shaped bearing portion 27 which cooperates with a lug portion 28 formed with the valve 15 for pivoting the latter on shaft 14 as shown in Figs. 1, 2 and 3, the spring 25 permitting the disengagement of plate 22 from the shaft 14 and thereby the removal of the valve 15 from the base 11, without necessitating the removal of shaft 14. The valve 15 is provided with an upwardly extending arm 29 which carries a stud 30 of insulating material for actuating contact springs 31 and 32 carried by a frame 33 for a purpose that will be hereinafter described in detail.

Frame 33 has oppositely disposed notches 34, one of them shown in Fig. 3 provided to fit over one of the lugs 12 and 13, to permit the mounting of this frame on the base 11, this frame being held in adjusted position by a number of screws 35.

On the frame 33 is pivotally mounted as on shoulder screws 40 and 41 a substantially U-shaped lever member 36 having one arm 37 extending in operable relation with a stud 38 carried by an upwardly extending flange portion 39 formed with the valve 15. The lever 36 and valve 15 are held in the unoperated position through the weight of valve 15 and the tension of contact spring 31 bearing against the stud 30 of plate 22. A bar 42 is secured to lever 36 by screws 50 and 51 and the movement of this lever is effective to engage and actuate the valve 15 from the closed position as shown in Fig. 3 to the position shown in Fig. 2 to permit the entrance of the ticket T in the tube 10. The undersurface or bearing portion of frame 33 registers with the configuration of base 11 as shown in Figs. 2 and 3 and a rack portion which is formed of a plurality of obliquely disposed bars 43, 44 and 45 is provided for receiving the ticket T preparatory to the opening of the valve 15 and to permit the air to enter the valve in the tube from both sides of the ticket, the operation of valve 15 simultaneously closing springs 31 and 32.

As shown in Fig. 4 on the inlet end of tube 10 is mounted a solenoid 46 provided for actuating a valve in the form of a flap member 47 against the resistance of a spring 48, the tension of which is controlled through the turning movement of a screw 49 for adjusting the air flow in the tube. Upon the energization of solenoid 46 the flap 47 is moved in line parallel to the direction of the tube thus decreasing the resistance of the air flow through the tube and thereby compensating for the air drawn in any 55

number of valves 15 which may be operated at the same time.

In a typical example of the operation of this device, the operator places the ticket T to be sent through the tube 10 upon the rack bars 43, 44 and 45 and simultaneously imparts a downward motion to the lever 36 for opening the valve 15 through the engagement of arm 37 with stud 38 thus causing the air to cross through the air paths formed by the bars 43, 44 and 45 to enter the tube from both sides of the ticket as indicated by the arrows in Fig. 2. This ticket is then drawn into the tube 10 through the conjoint action of the air flow on its sides and the bar 36 released for closing the valve. The closing of springs 31 and 32 causes the energization of magnet 46 through the circuit shown for actuating the flap member 47 for decreasing the resistance of the air blow at that point and thereby compensating for the air drawn in the tube from any number of valves which may be operated at the same time thus assuring the positive entrance of the tickets in any of these valves which are disposed nearest to the air inlet end of the tube.

It is to be noted that through the medium of this arrangement of parts it is possible for the operators either at the left or right position with the use of only one hand to conveniently and speedily dispatch tickets into the tube since this operation is effected by simply placing the ticket onto the rack formed by the bars 43, 44 and 45 and operating the bar 42 for opening the valve. These bars permit the air to enter the tube from both sides of the ticket which is thereby drawn into the tube and effectively prevented from being held on the incline as would be the case should the air be permitted to enter the tube from only one side of the ticket, while the provision of the valve operating mechanism affords the maximum of convenience to the opera-

tors and correspondingly effects a great saving of time in the dispatching operation of such tickets.

What is claimed is:

1. In a ticket sending valve, the combination with a pneumatic tube, a base soldered to said tube, the tube and said base having registering openings, a valve supported by said base normally closing said opening, a frame mounted on said base having an obliquely disposed rack extending adjacent the front edge of said valve for guiding the ticket toward the opening in said base, a stud carried by said valve and extending through an opening in said frame, a manually operable bar pivoted on said frame having an arm engaging said stud for operating said valve, said rack permitting the air to enter the pneumatic tube from both sides of the ticket for drawing it in said tube. 5 10 15

2. In a ticket sending valve, the combination with a pneumatic tube having an opening, a base welded to said tube and having a seat and an opening registering with the opening of said tube, a frame having a bearing surface engaging said base and a plurality of obliquely disposed bars extending toward said openings for receiving the ticket, said bars forming a plurality of air paths for permitting the flow of air to pass thereacross the impinge on the under surface of the ticket in conjunction with the flow of air on the top surface of the ticket for drawing it into said tube upon the operation of said valve, means for securing said frame on said base and a manually operable lever mechanism mounted on said frame, said mechanism 25 30 35 permitting the operation of said valve simultaneously with the placing of the ticket on said bars. 40
